(57) **CLAIM**

The ornamental design for a battery cover, as shown and described.

DESCRIPTION

FIG. 1 is a front, top, and right-side perspective view of a battery cover according to a first embodiment of the present invention, in which the access panel of the battery cover is in the secured position.

FIG. 2 is a top plan view of the battery cover shown in FIG. 1;

FIG. 3 is a bottom plan view of the battery cover shown in FIG. 1;

FIG. 4 is a back-side elevational view of the battery cover shown in FIG. 1;

FIG. 5 is a front-side elevational view of the battery cover shown in FIG. 1;

FIG. 6 is a right-side elevational view of the battery cover shown in FIG. 1;

FIG. 7 is a left-side elevational view of the battery cover shown in FIG. 1;

FIG. 8 is a front, top, and right-side perspective view of a battery cover according to the first embodiment of the present invention, in which the access panel of the battery cover is in the unsecured position;

FIG. 9 is a top plan view of the battery cover shown in FIG. 8;

FIG. 10 is a left-side elevational view of the battery cover shown in FIG. 8;

FIG. 11 is a right-side elevational view of the battery cover shown in FIG. 8;

FIG. 12 is a front, top, and right-side perspective view of an access panel of a battery cover according to the first embodiment of the present invention;
FIG. 13 is a top plan view of the access panel of the battery cover shown in FIG. 12;
FIG. 14 is a bottom plan view of the access panel of the battery cover shown in FIG. 12;
FIG. 15 is a front-side elevational view of the access panel of the battery cover shown in FIG. 12;
FIG. 16 is a back-side elevational view of the access panel of the battery cover shown in FIG. 12;
FIG. 17 is a right-side elevational view of the access panel of the battery cover shown in FIG. 12;
FIG. 18 is a left-side elevational view of the access panel of the battery cover shown in FIG. 12;
FIG. 19 is a front, top, and right-side perspective view of a battery cover according to a second embodiment of the present invention, in which the access panel of the battery cover is in the secured position.
FIG. 20 is a top plan view of the battery cover shown in FIG. 19;
FIG. 21 is a bottom plan view of the battery cover shown in FIG. 19;
FIG. 22 is a back-side elevational view of the battery cover shown in FIG. 19;
FIG. 23 is a front-side elevational view of the battery cover shown in FIG. 19;
FIG. 24 is a right-side elevational view of the battery cover shown in FIG. 19;
FIG. 25 is a left-side elevational view of the battery cover shown in FIG. 19;
FIG. 26 is a front, top, and right-side perspective view of a battery cover according to the second embodiment of the present invention, in which the access panel of the battery cover is in the unsecured position.
FIG. 27 is a top plan view of the battery cover shown in FIG. 26;
FIG. 28 is a right-side elevational view of the battery cover shown in FIG. 26;
FIG. 29 is a left-side elevational view of the battery cover shown in FIG. 26;
FIG. 30 is a front, top, and right-side perspective view of an access panel of a battery cover according to the second embodiment of the present invention;
FIG. 31 is a top plan view of the access panel of the battery cover shown in FIG. 30;
FIG. 32 is a bottom plan view of the access panel of the battery cover shown in FIG. 30;
FIG. 33 is a front-side elevational view of the access panel of the battery cover shown in FIG. 30;
FIG. 34 is a back-side elevational view of the access panel of the battery cover shown in FIG. 30;
FIG. 35 is a right-side elevational view of the access panel of the battery cover shown in FIG. 30;
FIG. 36 is a left-side elevational view of the access panel of the battery cover shown in FIG. 30;
FIG. 37 is a front, top, and right-side perspective view of a battery cover according to a third embodiment of the present invention, in which the access panel of the battery cover is in the secured position.
FIG. 38 is a top plan view of the battery cover shown in FIG. 37;
FIG. 39 is a bottom plan view of the battery cover shown in FIG. 37;

FIG. 40 is a back-side elevational view of the battery cover shown in FIG. 37;
FIG. 41 is a front-side elevational view of the battery cover shown in FIG. 37;
FIG. 42 is a right-side elevational view of the battery cover shown in FIG. 37;
FIG. 43 is a left-side elevational view of the battery cover shown in FIG. 37;
FIG. 44 is a front, top, and right-side perspective view of a battery cover according to the third embodiment of the present invention, in which the access panel of the battery cover is in the unsecured position;
FIG. 45 is a top plan view of the battery cover shown in FIG. 44;
FIG. 46 is a left-side elevational view of the battery cover shown in FIG. 44;
FIG. 47 is a right-side elevational view of the battery cover shown in FIG. 44;
FIG. 48 is a front, top, and right-side perspective view of an access panel of a battery cover according to the third embodiment of the present invention;
FIG. 49 is a top plan view of the access panel of the battery cover shown in FIG. 48;
FIG. 50 is a bottom plan view of the access panel of the battery cover shown in FIG. 48;
FIG. 51 is a front-side elevational view of the access panel of the battery cover shown in FIG. 48;
FIG. 52 is a back-side elevational view of the access panel of the battery cover shown in FIG. 48;
FIG. 53 is a right-side elevational view of the access panel of the battery cover shown in FIG. 48;
FIG. 54 is a left-side elevational view of the access panel of the battery cover shown in FIG. 48;
FIG. 55 is a front, top, and right-side perspective view of a battery cover according to a fourth embodiment of the present invention, in which the access panel of the battery cover is in the secured position.
FIG. 56 is a top plan view of the battery cover shown in FIG. 55;
FIG. 57 is a bottom plan view of the battery cover shown in FIG. 55;
FIG. 58 is a front-side elevational view of the battery cover shown in FIG. 55;
FIG. 59 is a back-side elevational view of the battery cover shown in FIG. 55;
FIG. 60 is a right-side elevational view of the battery cover shown in FIG. 55;
FIG. 61 is a left-side elevational view of the battery cover shown in FIG. 55;
FIG. 62 is a front, top, and right-side perspective view of a battery cover according to the fourth embodiment of the present invention, in which the access panel of the battery cover is in the unsecured position;
FIG. 63 is a top plan view of the battery cover shown in FIG. 62;
FIG. 64 is a right-side elevational view of the battery cover shown in FIG. 62;
FIG. 65 is a left-side elevational view of the battery cover shown in FIG. 62;
FIG. 66 is a front, top, and right-side perspective view of an access panel of a battery cover according to the fourth embodiment of the present invention;
FIG. 67 is a top plan view of the access panel of the battery cover shown in FIG. 66;

FIG. 68 is a bottom plan view of the access panel of the battery cover shown in FIG. 66;

FIG. 69 is a front-side elevational view of the access panel of the battery cover shown in FIG. 66;

FIG. 70 is a back-side elevational view of the access panel of the battery cover shown in FIG. 66;

FIG. 71 is a right-side elevational view of the access panel of the battery cover shown in FIG. 66; and,

FIG. 72 is a left-side elevational view of the access panel of the battery cover shown in FIG. 66.

The broken lines shown in the drawings are for the purpose of illustrating portions of the battery cover that form no part of the claimed design. In addition, the surface shading, if any, illustrated in the drawings is provided merely to highlight the contour of the design; it is not intended to be illustrative of texture or gloss.
